US00D878916S

(12) **United States Design Patent** (10) Patent No.: **US D878,916 S**
(45) Date of Patent: **** Mar. 24, 2020**

(54) **CONTAINER CAP**

- (71) Applicant: **TARGET BRANDS, INC.**, Minneapolis, MN (US)
- (72) Inventors: **Richard P. Riedel**, Blaine, MN (US); **Timothy Martell**, Minneapolis, MN (US); **Michael M. Habig**, Cincinnati, OH (US); **Ryan P. McCoy**, Falcon Heights, MN (US); **Terrence J. Hornsby, Jr.**, Minneapolis, MN (US)
- (73) Assignee: **TARGET BRANDS, INC.**, Minneapolis, MN (US)
- (**) Term: **15 Years**
- (21) Appl. No.: **29/663,861**
- (22) Filed: **Sep. 19, 2018**

CLAIM

The ornamental design for a container cap, as shown and described.

DESCRIPTION

FIG. 1 is a top perspective view of a container cap of showing an embodiment of our new design;
FIG. 2 is a bottom perspective view thereof;
FIG. 3 is a front view thereof, the rear view being a mirror image of the front view;
FIG. 4 is a right side view thereof, the left side view being a mirror image of the right side view;
FIG. 5 is a top view thereof; and
FIG. 6 is a bottom view thereof.
FIG. 7 is a top perspective view of a container cap of showing an embodiment of our new design;
FIG. 8 is a bottom perspective view thereof;

FIG. 9 is a front view thereof, the rear view being a mirror image of the front view;

FIG. 10 is a right side view thereof, the left side view being a mirror image of the right side view;

FIG. 11 is a top view thereof; and

FIG. 12 is a bottom view thereof.

FIG. 13 is a top perspective view of a container cap of showing an embodiment of our new design;

FIG. 14 is a bottom perspective view thereof;

FIG. 15 is a front view thereof, the rear view being a mirror image of the front view;

FIG. 16 is a right side view thereof, the left side view being a mirror image of the right side view;

FIG. 17 is a top view thereof; and

FIG. 18 is a bottom view thereof.

FIG. 19 is a top perspective view of a container cap of showing an embodiment of our new design;

FIG. 20 is a bottom perspective view thereof;

FIG. 21 is a front view thereof, the rear view being a mirror image of the front view;

FIG. 22 is a right side view thereof, the left side view being a mirror image of the right side view;

FIG. 23 is a top view thereof; and

FIG. 24 is a bottom view thereof.

FIG. 25 is a top perspective view of a container cap of showing an embodiment of our new design;

FIG. 26 is a bottom perspective view thereof;

FIG. 27 is a front view thereof, the rear view being a mirror image of the front view;

FIG. 28 is a right side view thereof, the left side view being a mirror image of the right side view;

FIG. 29 is a top view thereof; and

FIG. 30 is a bottom view thereof.

FIG. 31 is a top perspective view of a container cap of showing an embodiment of our new design;

FIG. 32 is a bottom perspective view thereof;

FIG. 33 is a front view thereof, the rear view being a mirror image of the front view;

FIG. 34 is a right side view thereof, the left side view being a mirror image of the right side view;

FIG. 35 is a top view thereof; and

FIG. 36 is a bottom view thereof.

FIG. 37 is a top perspective view of a container cap of showing an embodiment of our new design;

FIG. 38 is a bottom perspective view thereof;

FIG. 39 is a front view thereof, the rear view being a mirror image of the front view;

FIG. 40 is a right side view thereof, the left side view being a mirror image of the right side view;

FIG. 41 is a top view thereof; and

FIG. 42 is a bottom view thereof.

FIG. 43 is a top perspective view of a container cap of showing an embodiment of our new design;

FIG. 44 is a bottom perspective view thereof;

FIG. 45 is a front view thereof, the rear view being a mirror image of the front view;

FIG. 46 is a right side view thereof, the left side view being a mirror image of the right side view;

FIG. 47 is a top view thereof; and

FIG. 48 is a bottom view thereof.

In the drawings, the broken lines depict unclaimed subject matter only and form no part of the claimed design.
